(57) **CLAIM**

The ornamental design for a paint bucket insert, as shown and described.

DESCRIPTION

FIG. 1 shows a perspective view of a paint bucket insert; FIG. 2 shows a front view of the paint bucket insert; FIG. 3 shows a rear view of the paint bucket insert; FIG. 4 shows a right side view of the paint bucket insert; FIG. 5 shows a left side view of the paint bucket insert; FIG. 6 shows a top plan view of the paint bucket insert; and, FIG. 7 shows a bottom plan view of the paint bucket insert. The shade lines in the Figures show contour and not surface ornamentation.

The broken lines shown in the Figures show portions of the paint bucket insert device which form no part of the claimed design.

1 Claim, 3 Drawing Sheets
